UNITED STATES PATENT OFFICE.

FLOYD GILLETTE SWAN, OF EUREKA, CALIFORNIA.

TIRE-CUTTING TOOL.

Application filed April 30, 1924. Serial No. 710,148.

To all whom it may concern:

Be it known that I, FLOYD GILLETTE SWAN, a citizen of the United States, residing at Eureka, in the county of Humboldt and 5 State of California, have invented certain new and useful Improvements in Tire-Cutting Tools, of which the following is a specification.

My invention relates to that class of tools 10 employed for cutting the rubber of pneumatic tires in order to enable the same to be separated from the fabric or to separate one layer of fabric from another.

The invention has for its object to provide 15 such a tool of a simple and effective construction that can be easily and cheaply manufactured and in which provision is made for the use of very thin cutting blades such as are commonly employed in safety razors, 20 thereby doing away with the necessity of frequent re-sharpening of the blades.

Heretofore in tools of this character the blades have been made of comparatively 25 thick material and require frequent re-sharpening, and further, adequate provision has not been made for the quick and effective adjustment of the projection of the blades that defines the depth of the cut to be made.

My invention provides means whereby 30 the projection of the blade may be increased or diminished to enable the material to cut through one or more thicknesses of the fabric as may be desired. My tool also provides a means whereby the fabric may be started 35 loose after the cut has been made.

In its more subordinate nature the invention resides in those novel details of construction, combination and arrangement of parts, all of which will be first fully described, then 40 be specifically pointed out in the appended claims and illustrated in the accompanying drawing, in which:—

Figure 1 is a side elevation of my tool.

Figure 2 is a top plan view of the same.

45 Figure 3 is an inverted plan view of a portion of my tool.

Figure 4 is an end elevation of the portion shown in Figure 3.

Figure 5 is a vertical cross section on the 50 line 5—5 on Figure 1.

Figure 6 is a section on the line 6—6 of Figure 5 looking in the direction of the arrow, the adjusting screw and knife blade being omitted.

55 Figure 7 is an elevation of the removable

clamp plate which forms the complementary part of the structure shown in Figure 6.

Figure 8 is a detail elevation of the knife blade.

In the drawing, in which like numerals of 60 reference designate like parts in all the figures, 1 is the shank of the tool which is curved upwardly and projected rearwardly to carry the handle 18 hereinafter again referred to.

The shank 1 of the tool is provided with a vertical extension 2 that has an overhanging portion 3 beneath which the clamp plate 6 is located, the shank 1 being recessed at 4 to receive the clamp plate 5, the parts 2, 6, 4 and 5 being complementary parts. The shank 1 and its extension 2 have vertical grooves 8 to receive the corresponding ribs 7 of the clamp plate 5. The surfaces 10 and 11 of the complementary parts are separated 70 at a distance sufficient to receive the thin wafer-like blade 12, the lower edge of which is rounded and sharpened to a thin edge, while the upper end of which is provided with a T-slot 13 to receive the T-head 14 of the adjusting screw 15.

The complementary parts 2 and 6 are provided with a thread-way 9 to receive the screw 15, which screw includes the head 16 by which it may be turned to raise or lower 85 the blade 12 and thereby retract or project the cutting edge thereof beneath the lower face of the shank 1.

The nose 21 of the shank is preferably rounded as indicated to facilitate the use of 90 the tool.

It will be noted that the thread-way 9 goes through the overhanging portion 3 which thereby forms a screw bearing for the screw to retain it in place when the clamp plate 5 is loosened or removed for the purpose of 95 adjusting or changing the blade.

The clamp plate 5 is secured by suitable countersunk screws 17 to the shank 1, and by tightening these screws 17, a sufficient 100 gripping action is had not only on the threads of the screw 15 but on the blade 12 itself to hold the blade against movement in the socket provided between the surfaces 10 and 11 and the ribs 7—7. To adjust the 105 blade it is only necessary to ease up on the screws 17, turn the screw head 16 until the blade edge is projected the desired distance and then tighten up again on the screws 17 to hold the parts firm in place.

The shank 1 may be extended through the handle 18 and curved downwardly, as at 19, and provided with a sharpened trowel-like blade 20 which can be used to get under the 5 layers of fabric and loosen them up after the cut has been made through the rubber or rubber and fabric thicknesses in the usual way.

From the foregoing description, taken in 10 connection with the accompanying drawing, it is thought the construction, operation and advantages of my invention will be clear to those skilled in the art to which it appertains.

15 What I claim is:

1. In a tool of the character stated, a shank having a vertical projection and a recessed portion, a complementary clamp plate associated with said recessed portion and said projection, said recessed portion and said projection and said clamp plate having a pair of rib and groove portions arranged to leave a knife chamber therebetween, said clamp plate and said vertical projection of the shank having a thread-way, an adjusting screw mounted in said thread-way, a blade held in said knife chamber and adapted to be engaged by said screw, and means for securing the clamp plate to the shank to grip the blade.

2. In a tool of the character stated, a shank having a vertical projection and a recessed portion, a complementary clamp plate associated with said recessed portion and said projection, said recessed portion and said projection and said clamp plate having a pair of rib and groove portions arranged to leave a knife chamber therebetween, said clamp plate and said vertical projection of the shank having a thread-way, an adjusting screw mounted in said thread-way, a blade held in said knife chamber and adapted to be engaged by said screw, and means for securing the clamp plate to the shank to grip the blade, said screw having a T-end and said knife having a T-slot to receive said T-end.

3. In a tool of the character stated, a shank having a vertical projection and a recessed portion, a complementary clamp plate associated with said recessed portion and said projection, said recessed portion and said projection and said clamp plate having a pair of rib and groove portions arranged to leave a knife chamber therebetween, said clamp plate and said vertical projection of the shank having a thread-way, an adjusting screw mounted in said thread-way, a blade held in said knife chamber and adapted to be engaged by said screw, and means for securing the clamp plate to the shank to grip the blade, said projection having a por-

tion overhanging said clamp plate and provided with a threaded aperture for said adjusting screw.

4. In a tool of the character stated, a shank having a vertical projection and a recessed portion, a complementary clamp plate associated with said recessed portion and said projection, said recessed portion and said projection and said clamp plate having a pair of rib and groove portions arranged to leave a knife chamber therebetween, said clamp plate and said vertical projection of the shank having a thread-way, an adjusting screw mounted in said thread-way, a blade held in said knife chamber and adapted to be engaged by said screw, and means for securing the clamp plate to the shank to grip the blade, said screw having a T-end and said knife having a T-slot to receive said T-end, said projection having a portion overhanging said clamp plate and provided with a threaded aperture for said adjusting screw.

5. In a tool of the character stated, a shank having a vertical projection and recessed to provide an overhanging portion, a complementary clamp plate associated with said shank to lie in said recessed portion beneath said overhanging portion, said vertical projection and said clamp plate having a thread-way and said overhanging portion having a threaded aperture aligning with said thread-way, an adjusting screw mounted in said aperture and thread-way and having a T-end, a wafer blade mounted between said shank and said clamp plate and having a T-slot to receive the T-end of said screw, means for securing said clamp plate to the shank to grip the blade, substantially as shown and described.

6. In a tool of the character stated, a shank having a vertical projection and recessed to provide an overhanging portion, a complementary clamp plate associated with said shank to lie in said recessed portion beneath said overhanging portion, said vertical projection and said clamp plate having a thread-way and said overhanging portion having a threaded aperture aligning with said thread-way, an adjusting screw mounted in said aperture and thread-way and having a T-end, a wafer blade mounted between said shank and said clamp plate and having a T-slot to receive the T-end of said screw, means for securing said clamp plate to the shank to grip the blade, said shank and its vertical projection having a pair of parallel vertical grooves and said adjusting clamp plate having a corresponding pair of ribs, between which pair of ribs the knife blade is located.

FLOYD GILLETTE SWAN.
